ROBERT C. HARTRAMPF AND OTTO B. HARTRAMPF, OF HILLSBORO, OREGON.

SORTING MACHINE.

Application filed August 13, 1927. Serial No. 212,750.

This invention relates to sorting machines for sorting fruits, vegetables, or other articles and is a continuation in part of our pending application, Serial Number 58,425, filed September 24, 1925.

One object of our invention is to provide a machine which may be conveniently changed so as to sort articles by weight or by size, at will.

10 Another object of our invention is to provide a sorting machine with means for carrying the articles to be sorted on the side only of one endless belt and also for facilitating thereby the performance of certain desirable functions.

15 A further object of our invention is to provide an article-container of distinctive novelty in respect to its functions, construction, and mode of operation.

20 Other objects of our invention will be apparent to one skilled in the art from the specification which follows and are therefore deemed unnecessary to enumerate.

25 What constitutes our invention will be hereinafter specified in detail and succinctly defined in the appended claims.

In the accompanying drawings, showing our invention in present preferred form of embodiment,

30 Figure I is a plan view of our machine complete, save for the omission of the feed hopper.

Figure II is a plan view of the feed hopper, omitted from the preceding figure.

35 Figure III is a vertical cross sectional view, partly in elevation, substantially on line III—III of Figure I, with parts broken away.

40 Figure IV is a longitudinal sectional view, partly in elevation, taken on the line IV—IV of Figure I, in order to illustrate details of article distributing mechanism.

Figure V is a view similar to the last, taken on the line V—V of Figure I.

45 Figure VI is a top plan view of a portion of the endless chain carrier of our machine showing details of one form of supporting means for one of our article-containers therein shown by way of example.

50 Figure VII is a side elevation of a por-

tion of the machine set for sorting articles by size, and taken on section line VII—VII of Figure VI.

Figure VIII is a sectional view taken on the line VIII—VIII of Figure VI, showing 55 the one article-container thereof in the closed position.

Figure IX is a top plan detail view of our machine showing only one article-container and modified actuating mechanism therefor, 60 but indicating three other article-containers which are omitted.

Figure X is a side elevation, partly in section, of a portion of the subject matter of Figure IX.

Figure XI is a section on the line XI—XI of Figure IX, showing modified form of trip lever and its co-operative guide for actuating it.

Figure XII is a similar view showing one 70 of the article-containers in open position, and showing the directly related parts of the modified form of supporting and carrying mechanism.

Figure XIII is a vertical diametrical section of one of the article-containers detached from all of the related mechanism.

Figure XIV is a detached horizontal section of the form of article-container illustrated in Figure VIII, but distinguished 80 therefrom by showing the article-container thereof in the open position.

Referring to the reference numerals on the drawings, 1 indicates a hopper arranged at one end of the machine, from which the 85 articles to be sorted are delivered to an inspection table 2 which is disposed in operative communication with the hopper. Inspection tables are well known in the art, and any suitable type of table preferred may 90 be employed in our machine.

The purpose of inspection tables generally, as it is in the present instance, is to subject the articles to be sorted to inspection and to the opportunity thereby afforded for 95 selection of them by hand in order to grade them by quality before they are delivered to the operation of the sorting machine for distributing by size or weight. The table 2 preferably comprises two travelling horizon- 100

tally disposed endless belts 3, from which articles are transferred by hand to discharge chutes 5, 6, 7 and 8, of which four, for example only, are shown. Said chutes extend endwise from the hopper 1 into operative relationship to the sorting mechanism hereinafter specified, and deliver each its contents, to one side or other of the machine, into article-containers 9 which preferably are expandible and contractible. An intermediate return chute 4 is also shown.

The bottom of each of the discharge chutes consists preferably of an endless conveyor belt 10 which, passing over a supporting backing strip 11, is driven endwise of the chutes by any suitable driving mechanism. Such driving mechanism may comprise, for example, transverse parallel rollers 12 and 13, disposed in operative terminal relationship to the strip 11, in combination with guide rollers 14 and 15 and a driving roller 16, which, being in operative communication with a motor, not illustrated, engages a loop of the belt 10 provided for the chute 8 between the said guide rollers as shown in Figure IV.

The belts 3 of the table 2 are preferably disposed therein on opposite sides, respectively, of the assemblage of discharge chutes in operative propinquity to the hopper 1, and constitute, conveyors for the table 2. They are of suitable width to accommodate articles supplied to them from the hopper, and to display them in one layer so that, upon inspection, they may be sorted and distributed by hand to the respective discharge chutes selected.

The belts 3 and 10 except the one last above mentioned are driven by any suitable driving mechanism, such for example as that shown, in part, in Figure V. With the omission of the guide roller 14 for causing the belt 3 to make a sharp back turn in their travel below the belt, said driving mechanism is substantially the same as that illustrated in Figure IV already described. Each one of the discharge chutes 5, 6, 7 and 8—as many as may be employed—is provided at its discharge end with a box-like member which is designated a loader. All the loaders being substantially identical, they are indicated by the numeral 17 without distinction.

In the preferred form of embodiment of our invention herein illustrated, the sorting machine comprises a pair of sidebeams 20 (see Figures I and III) which are suitably spaced apart in parallel longitudinal relationship, and are, by any suitable means, not illustrated, supported at a convenient height above the floor on which the machine rests. They may be made of any suitable material such, for example, as wood or metal, and are provided, respectively, with grooves 21 in

their upper faces, as is well illustrated, for example, in Figure VIII, for the reception, preferably in countersunk relationship to it, of a flexible carrier. Said carrier is preferably an endless sprocket chain composed, for example, of a succession of links 22 (see Figure IX). Two sprocket wheels 24 and 25 carried, respectively, the former as by a vertical post 26, and the latter on a vertical rotative shaft 27, are provided near opposite ends of the machine, as shown in Figure I, to carry the sprocket chain aforesaid, with the links 22 of which the teeth of said sprocket wheels respectively intermesh. One of the sprocket wheels, 24 for instance, is an idler, which a mere post 26 may revolvably carry. The wheel 25 is the driving wheel for the carrier and is rotated by any preferred form of driving mechanism, unnecessary to illustrate or describe in detail. A special reason for the preference expressed above for the use of a sprocket chain form of flexible carrier above named, in addition to those offered by its many recognized mechanical advantages, is that said chain may be made easily separable into desired lengths by aid of the links 22. Thereby, a chain carrier may be easily increased or diminished in length by mere addition or subtraction of links as occasion may demand. Consequently the capacity of any given machine may be varied, at will, simply by variation of the length of the side-beams 20, to accommodate such length of the sprocket chain as it may be desirable to employ. For the accomplishment of that end, our invention comprehends the manufacture of the said side-beams in sections of convenient standard lengths each section being provided with terminal flanges 28 for securing one section to another in end to end abutment, as shown for example only, in Figure X.

The article-containers 9 are illustrated as carried by the sprocket chain aforesaid, each container being operatively connected with any predetermined link 22 thereof, whereby said containers may be secured to the chain at equally spaced intervals, as indicated in Figure I, wherein an example of a full complement of containers is illustrated. The tripping mechanism by which each of said containers is made to operate when secured to its link comprises a suitable supporting member, which is shown, for example, in Figures VI, VII, VIII and XIV, and which preferably consists of a supporting arm herein identified as a whole by its constituent elements, namely, terminal portions 29 and 30 and an intermediate portion 31. The portion 29 at one end of said arm is in effect a rock-shaft and is carried, preferably, in a bracket 32 provided with upstanding opposite terminal lugs 33 having coaxially aligned bearing-openings for said shaft 29.

The part 31 of said supporting arm, extending substantially at right angles to the said rock-shaft 29, is arranged parallel to the adjacent side-beam 20 of the machine, so as to 5 extend longitudinally above an elongated shelf-extension 36 which is preferably made a part of the bracket 32, and is provided with aligning members 34 and 35 for holding the member 31 in proper alignment to 10 the extension 36. The said terminal portion 30 of said arm, formed by a bend in the arm or otherwise as shown in Figures VI, VII and VIII, constitutes a direct support for a container 9, and is, for that purpose, preferably provided at its outer end with a pintle-ring 37, which may be secured to or made integral with it.

The ring 37 constitutes, in effect, an annular pintle for a plurality of pendant clip members, each of which preferably consists of a segment 38 having an apertured bearing 39 at its upper end for reception of the ring 37. Each article-container 9 in its present preferred form, is when closed, a downward tapered conical pocket. Each segment is provided with two annular series of wings 40 and 41. Said wings extending one from one side of each segment and one from the opposite side thereof are adapted to slidably engage the two next adjacent segments on each side of each individual segment. The assemblage of a complement of segments just described constitutes a pendant pocket-like container as above stated and the effect 35 of the mode of assemblage specified is to cause all the segments thereof to move in unison upon actuation of any individual segment on its bearing 39. Such movement of a segment towards the central axis of the conical container 9 tends to effect closure of the container, while movement of any segment away from said axis opens the container. The actuation of all the segments being thus made dependent upon the motion 45 of any one of them, any one of the segments may serve as the prime mover to all of them. The downward conical taper of the container effects the gradual descent into the container of an article within it according to size of the article and a final discharge therefrom of an 50 article of maximum size, only when the container is fully open. Each container 9 is adapted through its conical shape to perform the function of centering to the container an article contained within it. The effect in 55 sorting articles by weight is to dispose the center of gravity of the article in the container with substantial accuracy. In sorting articles by size the segments of each container operates with caliper effect on an article contained therein so as to gauge its size with accuracy.

A trip lever 46 for the container, as it is shown in the device illustrated in the figures last named, is provided as means for ac-

tuating the master segment. It is pivotally mounted on the terminal portion 30 of the container-supporting-arm, and is, as by a spring 47, yieldingly held in normal operative position thereon for actuating the master segment in one direction as herein-after described. Said spring is shown, by way of example, as one coiled around said terminal portion 30, and having its one end 48 secured to the lever 46 and its other end 49 secured to the terminal portion 30. A protective smooth-surfaced cover for the spring 47 is provided as a bearing member, preferably in the form of an enveloping sleeve 50.

On the terminal portion 30, is also mounted a pair of cams 52 and 53, either of which, by rotative movement imparted to one or the other, may be made, by movement of the trip lever 46, to engage and actuate the master segment through its extension 45. One of said cams being employed to close the article-container 9 when the machine is sorting by size, and the other being employed to close the article-container when the machine is sorting by weight, the cams are made alternately operative, that is to say, only one at a time. The cam 52 is the one employed to close the containers when the machine is sorting by size. It is, for operative reasons, made of wider transverse extent than the cam 53, and is provided with a relatively long gradual cam face 55. The second cam 53 being narrower than the cam 52, as shown by comparison of Figures VI, VII and VIII, is brought into requisition only when the machine is sorting by weight and when the cam 52 is moved out of its way. It is mounted on the member 30 preferably between the cam 52 and the projection 45, and is provided with an abrupt or relatively short cam face 57 as shown in Figures VI and VII. Either one of the cams, for example the cam 52 is, as shown in Figure VII, provided with an arcuate slot 59 adapted to receive a set screw 60, carried by the other cam, say 53, in a conveniently accessible position to permit relative adjustment of the said cams. When either of the cams is moved to inoperative position the other thereby becomes operative, and adjustment in desired position is secured by the said screw 60.

On opposite sides, respectively, of the machine, we provide below the line of travel of the containers a plurality of bins 61 and 62 (see Figures I and III) which are adapted to receive articles as they are dropped one by one, successively, from the containers 9 through operation of suitable tripping mechanism.

Above these bins, for cooperation with the form of tripping mechanism which we have described, we provide, for each bin, upon the sides of the respective side-beams 20,

fixed plates 63, each having a vertically disposed slot 64 therein and a suitable trip member 65 that is adapted to be adjustably fixed in said slot, as shown for example in Figure VII. The successive trip members 65 are, by their proper adjustments, respectively, adapted to be made to engage, in effect, the successive trip levers 46 in their travel, irrespective of whether the machine 10 is sorting by size or by weight.

For adapting the machine for the sorting of articles by weight, each of the plates 63 is provided at its upper end with a fixed horizontal guide plate 66 having an opening therein for the reception and guidance of a vertical arm 68. Each arm 68 is surrounded by and united to an elongated weighing platform 69, and is pivotally connected, as indicated at 71, to a scale beam 20 70 which is in turn fixedly fulcrumed to the plate 63, as at 72, each of the scale beams having an adjustable poise 73.

When the machine is sorting articles by size, the trip members 65 are severally adjusted at different levels in their respective slots 64. They are, by preference, in the operation of sorting articles by size, operatively connected one to another in their order of succession by tracks 75 (See Figure 25 VII), upon which the trip levers 46 successively may ride in the travel of the endless carrier identified by the links 22 which it preferably comprises. The tracks 75 are, 30 by proper adjustment of their terminal supporting members 65 at different heights, inclined from the horizontal, so that they will operate successively, to impart, for each track, a gradual opening movement to the successive article-containers through relative 35 adjustment of their respective trip levers 46. The shelf extensions 36 of the brackets 32, it may be noted in this connection, are shown in some of the figures as provided each with a movable catch 76 which is made 40 adjustable so as to engage and confine the part 31 of its proper supporting arm and locking it against the said extensions 36, respectively, when the machine is sorting by size. In such case, the function of the 45 respective catches 76 is to prevent vertical uplift, under impulse of the trip levers 46, of the article-container that is confined by its respective catch. It will be noted that by 50 reason of the pivotal connection of the container 9 to the endless carrier, that the former may be moved into an inoperative position so as not to be actuated by the trip mechanism.

In Figures IX, X, XI, and XII, no catch 60 76 is shown, because the weight of the container and contents may supply its place to hold down the member 31 in all instances.

The above described tripping mechanism 65 may be conveniently identified by the presence of the trip lever 46 as forming a part

thereof. A modification of the tripping mechanism is illustrated in Figures IX, X, XI and XII. In that modification, the same form of container 9 is preferably employed as in the other form, and likewise a substantially identical supporting arm therefor is used. The parts of said supporting arm are, for convenience, indicated, respectively, by numerals 79, 80, and 81, though they are, in effect, the same elements 75 previously indicated, respectively, by numerals 29, 30, and 31.

In the figures last enumerated the element 80 is shown as threaded to a boss 84, projecting from the master segment identified for the instance by numeral 86, and as supported by a side-beam 20, so as to render the container 9, in operation, pendent from the member 80.

Adjacent to the boss 84 a finger 87 extends from a rigid connection with the pintle ring 37 (compare Figures XI and XII). The said finger is yieldingly held in vertical position by a tensile spring 89 fastened at its opposite ends, respectively, to the said finger and to the member 80. Its free end laterally engages in operation (see Figures IX, X, XI, and XII) a stationary actuating rail 90. The finger 87 is contradistinguished from the trip lever 46, for which the finger 87 is substituted in the modification under present consideration, by being made subject to lateral actuation instead of the actuation in a vertical plane by the trip lever 46. Also the rail 90 is, in effect, a trip member for the finger 87.

Said rail is fixed at one end to an eyelet bolt 91 to which its connection is made pivotal for purpose of adjustment hereinafter explained. The bolt 91 penetrates an aperture provided for it in the beam 20, where-to it is fixed as by nuts 92 and 93 threaded to the bolt and disposed on opposite sides of said beam. A takeoff strip 95 from the rail 90 is pivoted to the said rail at one end, as indicated at 96, to a bearing piece 97 provided as by a bend in said rail.

Normally, the free end of the strip 95 is yieldingly pressed against the beam 20 as by a spring 99 coiled about the bearing piece 97 and operatively secured at one end to it and at the other end to the strip 95. The function of the strip 95 is to afford an adjustable inclined plane, as shown in Figure IX, for the free end of the finger 120 87 to ride upon for closing the container 9 in the operation of the machine. The end of the rail 90 which carries the bearing piece 97 is supported by an eyelet-bolt 100 which is held, as shown in Figure X, between nuts 101 and 102, threaded to said bearing piece. The stem of the bolt 100 may be secured, as shown in Figure IX, by nuts 103 and 104 disposed on opposite sides of the beam 20 and threaded to said stem.

Said stem is elongated sufficiently to accommodate between its nut 104 and the beam 20 an expansive coiled spring 105 as shown in Figure IX. By adjustment of the nuts 5 103 and 104, the distance between the eyelet of the bolt 100 and the beam 20 may be increased or diminished with the effect of regulating the angle of inclination of the strip 95 in relation to the beam 20, and 10 thereby of determining the course of the finger 87, after passing the end of the rail 90 which is supported by the bolt 100.

At the opposite end of the rail 90 from that which the eyebolt 100 supports, there 15 is provided a guide strip 106 which is, as indicated at 107, secured to and fulcrumed upon a tension bolt 108 that extends through an aperture in the beam 20. A nut 109 threaded to the inner end of the bolt 108, 20 secures, between it and the beam 20, an expansive spring 110 coiled about the bolt 108.

The purpose and effect of the spring 110 is yieldingly and adjustably to draw the free end 111 of the guide strip 106 into 25 firm contact with the bent end 112 of the rail 90, by which said rail is fastened to the eyebolt 91, preferably in like manner as its other end is coupled to the eyebolt 100. The strip 106 may be turned on its bolt 30 108 as shown in Figure X.

In combination with the modification of the tripping mechanism last described, we may employ a modified weighing mechanism instead of that previously described 35 comprising a lifting lever 115, over which the member 80 travels when the machine is in operation of sorting by weight. The lever 115 is pivoted to the beam 20 as indicated at 116. A rotatable stop piece 117 40 also is fixed to the beam in the path of movement of the lever 115 which is yieldingly drawn against the stop piece as by a tensile weighing spring 118, which is fastened at one end to the said lever and at 45 the other with means of tension adjustment 119 to the beam 20. The stop piece 117 in one position serves to hold the lever 115 flush with the top of the beam 20 as shown in dotted lines in Figure X. In its other 50 position it permits the lever 115 to assume, with weighing effect, the position shown in full lines in said figure.

Besides what is already specified, it should 55 be added that we prefer to use above each of the side beams 20 an aligning rail 120, each of which, at intervals along the beam 20 is supported by bent arms 121 upon which the rails 120, respectively, are mounted and fastened to the beams 20. Each rail 120 60 is designed and adapted to engage the tops of one line of the lugs 35 of the brackets 32 so as to compel the brackets to maintain substantially true horizontal alignment during the travel of the carrier in its respective 65 grooves 21.

Moreover, the loader 17, aforesaid, and its operation, require further description. The office of each loader, of which, as previously specified, one is provided for each of the discharge chutes, is to deliver articles to 70 the containers 9 in regular succession of travel. For effecting such delivery, each loader is preferably provided with a flexible sheet as of fabric, preferably canvas as 75 shown in Figures III and IV. Each sheet of fabric is supported on opposite sides by frame pieces 124 and 125, so as to form between them a depending flexible trough 126 into which the articles to be sorted are discharged from the chute appropriated to any given loader 17. The frame piece 125 is suitably fastened to a beam 20, the piece 124 being carried by the piece 125 by means of overhanging supports 128 and 129, the latter being of a sufficient height above the trough 80 85 126 for clearance of articles contained in said trough. The piece 124 preferably consists of a padded shelf upon which articles may be gently dropped from the discharge chute communicating therewith. 90

The bottom of each depending trough 126 makes contact with the tops of the bearings 39 of the respective containers 9 as they travel in continuous succession underneath them. The pintle rings 37 are slightly up- 95 tilted on one side as indicated in Figure IV with the effect of dividing the flexible bottom portion 126 of each apron into ridges 130 formed in the fabric of the apron by presence underneath it of the bearings 39. 100 Said ridges serve, each as a sort of dam, to hold the articles apart while they are traveling in the trough of the apron, and to drop them one by one into the containers 9 preparatory to the sorting operation of the machine. A terminal skirt 132 at the discharge end of the trough 126 serves to deposit each article as it leaves the loader 17 gently and with certainty into the container 9 which is 105 presented for its reception. 110

Description of operation follows:

The machine embodying the tripping mechanism shown in Figures VI, VII, and VIII, for instance, when employed for sorting by size, operates as follows. 115

The cam 52 is in such case the operative cam, and the cam 53 is moved to its inoperative position wherein it is secured by adjustment of the set screw 60 at the upper end of the arcuate slot 59. In said positions 120 of the cams 52 and 53 the face of the cam 52 extends beyond the face of the cam 53 and thereby excludes the cam 53 from contacting operation with the extension 45. The construction of the article-containers as 125 specified is such as to impart, at all times, to the segments composing them a constant tendency to assume an open position, preferably under action of gravity; but either one or other of the cams 52 and 53 by en- 130

gagement with the projection 45 of the master segment, operates to counteract that tendency by causing the master segment to swing upon its bearing 39.

5 The effect of said swinging movement of the master segment is to cause, in the manner already described, the segments to move towards the position for closing the article-container, as shown, for example, in Figure 10 VIII. When the trip lever 46 moves either one of its cams out of engagement with the extension 45, the article-container, which the said extension actuates, is thereby made free to open to the extent permitted by the 15 degree of rotative motion of the lever 46 so imparted, and the weight of the article the container holds causes proportionate movement of the lower ends of all the segments 38 outwardly towards the ultimate 20 position occupied by them when the container is open. When the opening of the container so effected is sufficient to permit the article the container holds to pass out of the container, said article will drop into 25 that one of the bins 61 or 62 that is selected by the sorting operation of the machine.

Each article-container, as it approaches, in the travel of its carrier, a trip member 30 65 will present its trip lever 46 tentatively to said trip member, which, if properly adjusted to permit required engagement between said members, will actuate the trip lever sufficiently to permit the article-container to open and release its contents. 35 Thereafter, the spring 47 will return the trip lever to its normal position, thereby closing the container so that it will then be ready immediately to receive another article to be sorted by size in like manner.

40 The trip members 65, of which one is shown in Figure VII of the drawings, are preferably connected successively by tracks 75 so that when an article-container is partially opened but insufficiently to drop its 45 contents in passing over one of the trip members 65, it will be, by coaction between its trip lever 46 and the track 75, retained in that partially opened position until it finds a trip member 65 or portion of a track 75 50 that is set high enough to actuate the lever 46 to a sufficient extent to permit its container 9 to drop its contents.

Upon mechanical selection of one bin for 55 each size of article, depends the performance of the sorting function of the machine.

Said selection of bins, in sorting articles by size, is effected as aforesaid by provision of a definite relativity between the length of the several tracks 75 and the width of 60 each bin. Upon reference to Figure VII, the length of the section of each track 75 being understood to be substantially equal to the width of the bin it is intended to serve, it will be obvious to one skilled in the 65 art that every time an article of a size

proper to be released by actuation of a certain trip lever 46 through its engagement with a determinate section of the track 75 is present, the occurrence of such engagement will cause said article to drop into the bin 70 which that track section serves and into no other.

It should also be observed, upon reference to Figure VII, that simply by the adjustment of any pair of the two track-supporting trip members 65 to the same level, the effect will be to amplify the stretch of any one track section 75 to the length of two, thereby appropriating two bins, for example, instead of one for the reception of articles of one size. In this manner extension of the track sections to any extent desired may be effected. This will be recognized as an advantage where the articles to be sorted run so largely to one size as to require increased bin capacity for the reception of articles of that size.

When sorting is to be made by weight instead of by size as we have just described, each lever arm 31 or 81, as may be employed, is released from its catch 76, and the cam 53 is, instead of the cam 52, moved to take operative position as shown in Figures IX and X of the drawings, it being observed that the arm 81 is, in effect, the same as the arm 31, and that it is interchangeable therewith in all forms of the machine. The article-containers 9 are thereby made free to move about the axis of the rock-shaft 29 of the supporting arm, but the downward movement of the lever arm 31 and of the article-container carried by its terminal extension 30 is limited by the shelf-extension 36 of the bracket 32.

When sorting of articles by weight is to be made, the trip members 65 are all adjusted to the same height in their respective slots 64. The poises 73 are, in sorting by weight, variously adjusted on the scale beams 70, respectively, so that different weights 100 must be placed on the different plates 69 so as to cause them, respectively, to be moved downwardly under a predetermined superposed weight. As often as an article-container passes, in effect, over one of the plates 69, the sleeve 50 thereof rides on the said plate. If now the weight of the content of said container is sufficient to overcome the weight of the poise 73 in the weighing position on its beam 70 to which 105 it is adjusted, the said plate 69 will move downwardly and permit downward movement of the article-container affected, together with its trip lever 46. This downward movement, if sufficient to bring the said trip lever into engagement with the trip member 65 next in order, will cause the said trip lever to swing on its bearing piece 30 in the arc of a circle, thereby causing the 110 face of the cam 53 to recede from the pro-

jection 45 of the master segment, thereby permitting the said segment and all the segments which the master segment controls, as aforesaid, to fall by gravity with consequent opening of the article-container and dropping of its contents. After such engagement between the trip lever and the trip member is effected by the travel of the carrier, the spring 47 returns the trip lever to its normal position, and the face of the cam 53 will reengage the projection 45 to close the article container through actuation by the master segment, in the manner heretofore described.

15 The machine whose operation has just been described is one embodying the form of tripping mechanism in which is included the trip lever 46 which functionates by movement in a vertical plane.

20 The tripping mechanism which functionates by a swinging movement of the finger 87, as will appear upon comparison of Figures XI and XII in view of the previous specification, in sorting articles by size, effects the opening of an article-container by lifting of the container to an inclined position as shown in Figure XII.

It may be understood from the foregoing description that articles may thus be sorted 30 into the bins 60 or 61 either by size or weight and thence removed for packing and shipment. It should be observed from the foregoing description that by certain simple adjustments, the machine may be readily converted from one which sorts articles by size to one which sorts them by weight, or in reverse order, at will.

40 It is to be understood that the form of embodiment of our invention herein shown and described is only that at present preferred, and that many changes in respect to shape, size and relative arrangements of parts, for example, are contemplated as within the scope of the invention as defined 45 in the appended claims.

What we claim is:

1. In a sorting machine, the combination with its frame, an endless flexible carrier, and carrier driving mechanism, of article-containers operatively communicating at spaced intervals with the carrier and extending outwardly from the side thereof, said containers consisting each of a ring, a plurality of depending clip members pivotally mounted on said ring, and means actuated by the straight travel of the carrier for swinging the clip members on their supporting ring for opening and closing the article-container.

60 2. In a sorting machine, the combination with its frame, an endless flexible carrier, and carrier driving mechanism, of article-containers operatively communicating at spaced intervals with the carrier and extending outwardly from the side thereof, said

containers consisting each of a ring, a plurality of depending clip members pivotally mounted on said ring, and means actuated by travel of the carrier for swinging the clip members on their supporting ring for opening and closing the article-container, said means consisting of an operative trip lever provided for each container, and a trip member on the frame in operative coacting relationship to its appropriate trip lever. 75

3. In a sorting machine, the combination with its frame, an endless flexible carrier, and carrier driving mechanism, of article-containers operatively communicating at spaced intervals with the carrier and extending outwardly from the side thereof, said container consisting each of a ring, a plurality of depending clip members pivotally mounted on said ring, and means actuated by travel of the carrier for swinging the clip members on their supporting ring for opening and closing the article-container, said means consisting of an operative trip lever provided for each container, and a trip member on the frame in operative coactive operative relationship only to its appropriate trip lever. 80

4. In a sorting machine, the combination with its frame, an endless flexible carrier, and carrier driving mechanism, of article-containers normally in a fixed position relative to the carrier and operatively communicating at spaced intervals therewith and extending outwardly from the side thereof, and means provided for each container that are adapted to open and close it under actuation 95 effected by the travel of the carrier.

5. In a sorting machine, the combination with its frame, an endless flexible carrier, and carrier driving mechanism, of article-containers operatively communicating at spaced intervals with the carrier and extending outwardly from the side thereof, said containers consisting each of a pintle ring, a plurality of depending clip members 105 pivotally mounted on said ring, and means actuated by travel of the carrier for swinging the clip members on said ring for opening and closing the article-containers, said means consisting of an operative trip lever 110 provided for each container, and a trip member on the frame in coacting operative relationship to its appropriate trip lever, said trip member being vertically adjustable at will. 120

6. In a sorting machine, the combination with its frame, an endless flexible carrier, and carrier driving mechanism, of article-containers operatively communicating at spaced intervals with the carrier and extending outwardly from the side thereof, said containers consisting each of a ring, a plurality of depending clip members pivotally mounted on said ring, and means actuated by travel of the carrier for swinging the clip 125 130

members on said ring for opening and closing the article-container, said means consisting of an operative trip lever provided for each container, a trip member on the frame in coacting operative relationship to its appropriate trip lever, said trip member being vertically adjustable at will, and trip lever supporting tracks for uniting a plurality of trip members.

10 7. In a sorting machine, the combination with its frame, an endless flexible carrier, and carrier driving mechanism, of article-containers operatively communicating at spaced intervals with the carrier, said containers each having a trip lever in operative communication with it, vertically adjustable trip members, track sections supported by and uniting adjoining trip members, and means for extending the length of adjoining track sections by corresponding adjustment of the respective supporting trip members.

15 8. In a sorting machine, the combination with its frame, carrier, and carrier driving mechanism, of article-containers each comprising clip members horizontally pivoted, respectively, to the carrier, means for each article-container actuated by travel of the carrier for opening and closing said clip members, said means comprising coacting members on the frame and on the carrier, respectively, that are adapted to be rendered inoperative by lifting at will any article-container on its pivotal connection with the carrier.

20 35. 9. In a sorting machine, the combination with its frame, carrier, and carrier driving mechanism, of article-containers each comprising movable clip members, means for each container actuated by the travel of the carrier for opening and closing a container by movement of its said clip members, said means including the employment of one clip member as a prime mover adapted to open and close all the clip members, and means for actuating said prime mover.

25 40. 10. In a sorting machine, the combination with its frame, carrier, and carrier driving mechanism, of article-containers each comprising movable clip members, means for each container actuated by the travel of the carrier for opening and closing a container by movement of its said clip members, said means including the employment of one clip member as a prime mover adapted to open and close all clip members, and means for actuating said prime mover, said last named means comprising a movable trip lever for each article-container, a coacting trip member therefor fixed to the frame, a projection on the prime mover, and a cam carried by the trip lever in operative propinquity to said projection.

45 50. 11. In a sorting machine, the combination with its frame, carrier, and carrier driving mechanism, of article-containers each com-

prising movable clip members, means for each container actuated by the travel of the carrier, for opening and closing a container by movement of its said clip members, said means including the employment of one clip member as a prime mover adapted to open and close all clip members, and means for actuating said prime mover, said last named means comprising a movable trip lever for each article-container, a coacting trip member therefor fixed to the frame, a projection on the prime mover, and a plurality of relatively adjustable cams carried by the trip lever and adapted by their relative adjustment, at will, to operatively engage said projection.

55 12. In a sorting machine, the combination with its frame, carrier, and carrier driving mechanism, of spaced article-containers in operative communication with the carrier each comprising movable clip members, means for opening and closing said clip members comprising a trip lever for each article-container, and trip members on the frame, a bin, and a track section of a length corresponding to the width of the bin connecting trip members and affording an extended supporting member for the trip lever.

60 13. As a member of a sorting machine, an article-container consisting of the combination of an annular pintle-support, and a series of clip members pivoted thereon, with cooperative members on said respective members adapted to operatively engage their next adjacent members for imparting the movement of one of said members to all of them simultaneously.

65 14. In a sorting machine, the combination with a frame, an endless carrier, and brackets mounted at spaced intervals on said carrier, of a container supporting-arm pivotally mounted in each of said brackets, an article-container carried each by one of said arms, means for locking said arms, respectively, in one position, a trip lever carried by each of said arms, and trip members operatively disposed in the path of said trip levers.

70 15. In a sorting machine, the combination with a frame, a plurality of article-containers, each comprising an arm, a pintle ring on the end of said arm, a plurality of depending segments arranged on said ring and adapted to be opened by gravity, a trip lever carried by each of said arms, means controlled by said trip lever for normally retaining each of said containers in closed position, trip members operatively disposed in the path of said trip levers, and an endless driven carrier in operative communication with the article-containers for imparting consecutive motion to them.

75 16. In a sorting machine, the combination with a frame, of a plurality of article-containers, each comprising an arm, a pintle ring on the end of said arm, a plurality of

depending segments arranged on said ring and adapted to be opened by gravity, a trip lever carried by each of said arms, cams carried by said trip levers to normally retain

5 said containers in closed position, trip members operatively disposed in the path of said trip levers, and an endless driven carrier in operative communication with the article-containers for imparting consecutive motion

10 to them.

17. A machine constructed in accordance with claim 16 wherein one segment of said article-container adjacent to said cam is provided with a projection adapted to be engaged thereby, and each of said segments is provided with wings adapted to engage the next adjacent segments to move all of them to closed positions.

18. In a sorting machine, the combination 20 with its frame, of a plurality of article-containers, an endless carrier therefor on which said containers are severally pivotally mounted, a trip lever carried by each of said containers, respectively, a weighing platform, a scale beam operatively connected to said platform, a poise adjustably mounted on said beam, a trip member for each container disposed adjacent said platform and adapted to be engaged by said trip lever when the weight of said container is sufficient to depress said platform.

19. In combination with a sorting machine, a frame, an endless carrier associated with the frame, expansible and contractible 35 containers having supporting arms extending therefrom, means pivotally connecting the end portions of each of said arms to the carrier, and means for actuating the containers to empty the contents thereof at predetermined points in their path of travel.

20. In combination with a sorting machine, a frame, an endless carrier associated with the frame, expansible and contractible 40 containers having supporting arms extending therefrom, means pivotally connecting the end portions of each of said arms to the carrier, means for maintaining said arms in fixed position relative to the carrier, and means for actuating the containers to empty 45 the contents thereof at predetermined points in their path of travel.

21. In combination with a sorting machine, a frame, an endless carrier associated with the frame, expansible and contractible 55 containers having supporting arms extending therefrom, means pivotally connecting the inner end portions of each of said arms to the carrier, means normally maintaining said containers in their closed position, and means for opening the containers at predetermined points in their path of travel.

22. In combination with a sorting machine, a frame, an endless flexible carrier associated with the frame, expansible and contractible 60 containers, each of said con-

tainers consisting of a ring, a plurality of depending clip members pivotally mounted on the ring, means pivotally connecting the ring to the carrier, means for normally maintaining the clip members in their closed position, and means for opening the clip members at predetermined points in their path of travel.

23. In combination with a sorting machine, a frame, an endless carrier associated 70 with the frame, article containers pivotally connected to the carrier, means for emptying the contents of each container, means operable by the size of the article for actuating said first mentioned means, means operable by the weight of the article for actuating said first mentioned means, and means for selectively sorting the articles in the containers either by size or weight.

24. In combination with a sorting machine, a frame, an endless carrier associated with the frame, expansible and contractible containers pivotally connected to the carrier, means for emptying the contents of each container at predetermined points in its 80 path of travel, means operable by the size of the article for actuating said first mentioned means, means operable by the weight of the article for actuating said first mentioned means, and means for selectively sorting the articles in the containers either by size or weight.

25. In combination with a sorting machine, a frame, an endless carrier associated with the frame, article containers connected 100 to said carrier and extending laterally therefrom, means for actuating the article containers to empty the contents thereof at predetermined points in their path of travel, delivery chutes communicating with a source 105 of supply of articles to be sorted and with said article containers, and a loader for each delivery chute positioned at one end thereof and in communication with article containers, each loader comprising a flexible trough 110 having its bottom in contact with the tops of the containers, said containers being tilted at one side so as to produce article spacing ridges in the bottom of the trough.

26. In combination with a sorting machine, a frame, an endless carrier associated with the frame, article containers connected to said carrier and extending laterally therefrom, means for actuating the article containers to empty the contents thereof at predetermined points in their path of travel, delivery chutes communicating with a source 120 of supply of articles to be sorted and with said article containers, a loader for each delivery chute positioned at one end thereof and in communication with the article containers, and a flexible skirt at one end of the loader for discharging the contents thereof to the container.

27. In combination with a sorting ma- 125

chine, a carrier element, means for discharging an article from the carrier element, means operable by the size of the article for actuating said first mentioned means, 5 means operable by the weight of the article for actuating said first mentioned means, and means for selectively sorting the article

on the carrier element either by size or weight.

In testimony whereof, we have hereunto 10 set our hands.

ROBERT C. HARTRAMPF.
